UNITED STATES PATENT OFFICE.

EDWIN J. MURPHY, OF SCHENECTADY, NEW YORK, ASSIGNOR TO GENERAL ELECTRIC COMPANY, A CORPORATION OF NEW YORK.

ELECTROMAGNETIC SWITCH.

1,109,245.

Specification of Letters Patent.

Patented Sept. 1, 1914.

Application filed June 5, 1913. Serial No. 771,794.

To all whom it may concern:

Be it known that I, EDWIN J. MURPHY, a citizen of the United States, residing at Schenectady, in the county of Schenectady, 5 State of New York, have invented certain new and useful Improvements in Electromagnetic Switches, of which the following is a specification.

My invention relates to electromagnetic 10 switches for controlling electric circuits, one of the objects of my invention being to provide a switch of this character which has a small number of parts, is simple and rugged in construction, and reliable and 15 efficient in operation.

In the drawings in which I have illustrated my invention, Figure 1 is a side elevation of the switch embodying my invention partly broken away to show the construction; Fig. 2 is a front elevation of the same; Figs. 3 and 4 are perspective views of the switch; and Fig. 5 is a detail of construction showing the electrical connections to the pivot of the switch contact.

Referring to the drawing, 10 represents the base of insulating material, to which is secured an L-shaped frame 11 of magnetic material such as iron or steel. This frame is secured to the base by bolts 12.

13 represents a winding for operating the switch and 14 is the core for the winding. The core is secured to the frame so as to make a good magnetic path for the flux between the core and the frame. The movable 35 contact member or switch arm consists of an armature member 15 which is in the form of a yoke having two arms 16 pivoted to the frame at 17. The switch shown in Figs. 1 and 2 is of the double pole type, that is, 40 there are two contacts insulated from each other on each switch. For each contact there is a contact support 18 consisting of a head 19 and a shank 20 which enters a perforation in the armature member as hereinafter described. Pivoted to each head is a contact 21 coöperating with a fixed contact 22 located in the arc chute 23, the contact being secured to the insulating base. The construction of the contact and the 50 means for making electrical connection therewith are shown in Fig. 5. The pivoted contact support is provided with two ears 24 one on each side of the contact, and a pivot pin 25 passes through the contact and is 55 prevented from turning by the pin 26. One

end of the pin is provided with a head that enters one of the ears and bears against the contact while the other end is screw-threaded and passes through a bushing 27 which also bears against the contact. The 60 flexible conductor is provided with a terminal 28 which is bent over the head of the bushing and a nut 29 locks the terminal between the head of the bushing and the nut. The flexible conductor is carried back and 65 connected through the base as shown. Good electrical connection is thus obtained between the support and the contact through the pivot pin without in any way impairing the mechanical efficiency of the pivotal connection. Between the head 19 and the contact proper is a spring 30 which is compressed when the contact 21 is turned on its pivot in engaging the fixed contact so as to make a wiping or rolling contact in a well- 70 known manner.

In Fig. 3 I have shown the construction of the armature member in the case of a double pole contactor. The armature is cast in one piece, as shown in Fig. 4 (but 80 without the aperture 31) and is then drilled with two apertures 32 and 33, and cut in two through the apertures so as to form the clamping member 34 shown in Fig. 3. Two shanks for the contact support are then 85 placed in the apertures with insulating material surrounding them so as to make a snug fit. Insulation is also placed between the head and the armature member as shown. The clamping member 34 is then placed over 90 them and a bolt 35 passed through the parts to hold them in place. With this arrangement it is possible to secure good insulation between the contact and the support and at the same time a good mechanical joint is 95 made between them. In case, however, the switch is of the single pole type, the same armature member is used, that is, the same casting is utilized, but inasmuch as it is unnecessary to insulate the contact the construction is much simpler. All that is necessary in this case is to drill a hole 31 into which the shank is inserted and a pin driven through the hole 36 to hold the shank in place. It will be noted that the pivotal 100 point 17 of the armature member is some distance back from the end of the frame 11 and the arms 16 are bent at an angle so as to bring the main armature body, the contacting face of which is marked 37, out beyond 105 110

the pivot. This makes it possible to support the switch arm in a position to be attracted by the core in a very simple manner. A screw having a head 38 is screwed into the under side of the armature body so as to engage the end of the magnet frame. By adjusting this screw head, the position of the switch member in its deenergized position may be determined with accuracy. It will thus be seen that the same parts are used for the single pole contactor as for the double pole contactor. The arrangement is such that a good, efficient, magnetic structure is produced with a small number of compactly arranged parts.

While I have described my invention as embodied in concrete form and as operating in a specific manner in accordance with the patent statutes, it should be understood that I do not limit my invention thereto since various modifications thereof will suggest themselves to those skilled in the art without departing from the spirit of my invention, the scope of which is set forth in the annexed claims.

What I claim as new and desire to secure by Letters Patent of the United States, is:

1. An electromagnetic switch comprising a frame of magnetic material, a magnetizing winding therefor, an armature pivoted to said frame, a contact support having a shank entering an aperture in the armature at substantially right angles to the axis of said armature, and a contact pivoted to said support on an axis parallel to the axis of the armature.

2. An electromagnetic switch comprising a frame of magnetic material, a magnetizing winding therefor, an apertured armature pivoted to said frame divided through the aperture into two parts, a contact support having a shank entering said aperture, means for securing the two parts together to clamp the support, and a contact pivoted to said support on an axis parallel to the axis of the armature.

3. An electromagnetic switch comprising

a frame of magnetic material, a magnetizing winding therefor, an armature pivoted to said frame, a shank entering an aperture having a head, a contact pivoted to said head, and a spring interposed between the head and the contact tending to turn the latter on its axis.

4. An electromagnetic switch comprising a frame of magnetic material, a magnetizing winding therefor, an armature pivoted to said frame, a shank entering an aperture in the armature at substantially right angles to the axis of said armature, a head for said shank, a contact pivoted to said head, and a spring interposed between the head and the contact tending to turn the latter on its axis.

5. An electromagnetic switch comprising a frame of magnetic material, a magnetizing winding therefor, an armature having two apertures pivoted to said frame and divided through the apertures into two parts, two contact supports each having a shank entering one of said apertures, means for securing the two parts together to clamp the supports, and a contact pivoted to each support on an axis parallel to the axis of the armature.

6. An electromagnetic switch comprising a frame of magnetic material, a magnetizing winding therefor, an armature having two apertures pivoted to said frame and divided through the apertures into two parts, two contact supports each having a head and a shank entering one of said apertures, means for securing the two parts together to clamp the supports, a contact pivoted to each head on an axis parallel to the axis of the armature, and a spring interposed between the head of the contact tending to turn the latter on its axis.

In witness whereof, I have hereunto set my hand this 3rd day of June, 1913.

EDWIN J. MURPHY.
